US00D999407S

(12) **United States Design Patent** (10) **Patent No.:** **US D999,407 S**
Bircham (45) **Date of Patent:** **** Sep. 19, 2023**

(54) **ENGINEERED WOOD PANEL WITH SURFACE ORNAMENTATION**

(71) Applicant: **Kronoplus Limited**, Mosta Malta (MT)

(72) Inventor: **Mark Edmund Bircham**, Rosenheim (DE)

(73) Assignee: **Kronoplus Limited**, Mosta (MT)

(**) Term: **15 Years**

(21) Appl. No.: **35/512,128**

(22) Filed: **Jun. 17, 2021**

(80) **Hague Agreement Data**

Int. Filing Date: **Jun. 17, 2021**

Int. Reg. No.: **DM/214864**

Int. Reg. Date: **Jun. 17, 2021**

Int. Reg. Pub. Date: **Jul. 2, 2021**

(51) **LOC (14) Cl. 25-01**

(52) **U.S. Cl.**

USPC **D25/150**
